UNITED STATES PATENT OFFICE.

GEORGE W. SWIFT, JR., OF BORDENTOWN, NEW JERSEY.

TAG-MACHINE.

No. 854,388.

Specification of Letters Patent.

Patented May 21, 1907.

Application filed January 17, 1906. Serial No. 296,460.

To all whom it may concern:

Be it known that I, GEORGE W. SWIFT, Jr., of Bordentown, in the State of New Jersey, have invented certain new and useful Improvements in Tag-Machines, whereof the following is a specification, reference being had to the accompanying drawings.

It is the object of my invention to provide a machine to form tags from continuously moving webs, without interrupting the progression of said webs, and to deliver either separate individual tags in lots of a predetermined number, or successive series of predetermined numbers of tags connected in gangs.

The form of my invention hereinafter described comprises reciprocatory punching mechanism arranged to punch disks from reinforcing webs disposed above and below the tag web, means to progress said reinforcing webs divergently, so as to discharge them aside from the tag web; and, means to press said disks into engagement with the opposite sides of said tags web, and to perforate said tag web and disks in concentric relation with the latter.

My invention also comprises reciprocatory cutting mechanism arranged to sever the tags from the web, and to cut the corners from said tags, and mechanism whereby the severing blades may be reciprocated to partially sever a predetermined number of tags, and then given an additional movement to sever in a gang, the series of tags thus formed.

My invention further includes mechanism arranged to detain the individual tags until a predetermined number are grouped, and then to deliver the group of tags to a suitable receiver.

My invention includes the various novel features of construction and arrangement hereinafter more definitely specified and claimed.

In the accompanying drawings, Figure I, is a plan view of a tag machine conveniently embodying my improvements. Fig. II, is a side elevational view of said machine as seen from the lower side of Fig. I. Fig. III, is a central vertical longitudinal section of said machine. Fig. IV, is a vertical transverse section taken on the line IV, IV, in Figs. II, and III, showing the punching mechanism in elevation, with its punches shifted to their maximum engagement. Fig. V, is a vertical transverse section taken on the line V, V, in Figs. II, and III, showing the cutting mech-

anism in elevation. Fig. VI, is a fragmentary vertical sectional view taken on the line VI, VI, in Fig. IV. Fig. VII, is a fragmentary transverse vertical sectional view taken on the line VII, VII, in Fig. V. Fig. VIII, is a plan sectional view of the punching mechanism taken on the line VIII, VIII, in Fig. IV. Fig. IX, is a plan sectional view of the cutting mechanism taken on the line IX, IX, in Fig. V. Fig. X, is a plan sectional view of the cutting mechanism taken on the line X, X, in Fig. V. Fig. XI, is a transverse vertical sectional view taken through the web guides on the line XI, XI, in Fig. I. Fig. XII, is a plan view of the tag-body web and the reinforcing webs as they are disposed in the machine. Fig. XIII, is a plan view of the severed tags. Fig. XIV, is a plan view of the gangs of tags severed from the web.

In said drawings,—1, is the supporting frame comprising the side frames 2, and 3, which have feet 4, and 5, respectively, and which are joined by the end frames 6, and 7. Said side frames 2, and 3, are provided with brackets 8, having suitable bearings 10, for the reel 11, carrying the roll 12, of paper web 13. Said web 13, is of such width as to form two rows of tags with their ends abutting which have their attaching apertures 14, punched in its outer edge, as shown in Figs. I, and XII, and is arranged to be longitudinally slit, preferably in proximity to the cutting mechanism.

The reinforcing disks 15, which surround the apertures 14, are punched from the upper and lower reinforcing webs 18, and 19, respectively, whose rolls 20, and 21, are mounted on the reels 22, and 23, suitably supported on the standards 24, and 25, respectively.

The main driving shaft 27, of the machine is provided with the usual tight and loose pulleys 28, and 29, and the gear 30, at one end; and with the hand wheel 31, at the outer end. Said gear 30, is in toothed engagement through the idlers 33, and 34, with the gears 36, and 37, on the shafts 38, and 39, of the punching mechanism and cutting mechanism, respectively. The shaft 38, is provided with the miter-gear 40, in toothed engagement with the miter-gear 41, on the counter-shaft 42, which has the miter-gear 43, in toothed engagement with the miter-gear 44, on the shaft 45, of the feeding roller 46, which co-operates with the roller 47, to feed the web 13, to the punching mechanism.

The punching mechanism is conveniently

supported by the bearing standards 48, and hangers 49, and comprises opposed cross-heads 50, and 51, carrying suitable punching dies for forming the reinforcing disks 15, depositing said disks on the web 13, by impacting thereon, and perforating said web 13, and its disks 15, in concentric relation with the latter. The gear 36, of said punching mechanism is arranged to rotate in the direction of the arrow shown in Fig. II, and to mesh with the gear 52, whose shaft 53, is journaled in the bearings 54, in the standards 48, and provided with the gear 55. Said gear 36, also meshes with the gear 56, whose shaft 57, is journaled in suitable bearings 58, in the hangers 49, and provided with the gear 59. The gears 52, and 55, mesh with the idle gears 60, which are mounted on the stud shafts 61, on the standards 48, and mesh with the gears 62, whose shafts 63, are journaled in the bearings 64, in said standards 48. Said shafts 63, are provided with the wrist plates 65, having the eccentric pins 66, engaging the connecting rods 67, to which the cross-head 50, is rigidly secured. The gears 56, and 59, mesh with the gears 68, whose shafts 69, are journaled in the bearings 70, in the hangers 49, and provided with the wrist plates 71, having the eccentric pins 72, engaging the connecting rods 73, to which the cross head 51, is rigidly secured.

The cross heads 50, and 51, are maintained in alinement by the guide bars 74, which are secured to the connecting rods 73, and are arranged to reciprocate in the slide-ways 78, in the connecting rods 67, being prevented from displacement by the cleats 75.

As best shown in Fig. VIII, the adjacent faces of the cross heads 50, and 51, are provided with the diagonal grooves 76, through which the respective reinforcing webs 18, and 19, are arranged to pass, and across which the die plates 77, are disposed in rigid relation with their respective cross heads.

The shafts 63, and 69, at the left of Fig. IV, carry the gears 80, and 81, which are concentric with the respective pins 66, and 72, and in toothed engagement with the gears 82, and 83, whose respective shafts 84, and 85, are journaled in the bearings 86, and 87, on the respective connecting rods 67, and 73. The shafts 84, and 85, are provided with cams 89, and 90, secured thereon, and arranged to oppositely reciprocate the links 91, and 92, whose cam rollers 93, and 94, traverse the grooves 95, and 96, in the respective cams 89, and 90, and in whose split heads 98, and 99, the plungers or punches 100, and 101, are adjustably secured by the tap bolts 102, and arranged to co-operate with the die plates 77, in forming the reinforcing disks, which they respectively deposit on opposite sides of the web 13. The shaft 84, is also provided with the cams 104, arranged to reciprocate the links 105, by cam rollers 106,

which are journaled on said links 105, and arranged to traverse the cam grooves 107. Said links 105, have a greater range of movement than the links 91, and carry the cutting tools or punches 108, adjustably secured by the set screws 109. As best shown in Fig. VI, said punches 108, extend through the punches 100, and are arranged to perforate the web and its reinforcing disks in concentric relation with the latter.

As best shown in Fig. VIII, four sets of punches are employed, and at each reciprocation of the cross heads, the web 13, is reinforced by disks 15, punched from the reinforcing webs, and perforated in regions to be subsequently divided into four tags, as best shown at the right hand end of Fig. XII. As indicated by the arrows in said figure, the reinforcing webs 18, and 19, are arranged to be progressed in divergent relation, adjacent to the tag web 13, and in such relation to the punches that the reinforcing disks 15, are punched from regions adjacent to the edges of said reinforcing webs and the punched residue discharged from opposite sides of the machine.

The webs 18, and 19, on each side of the machine pass from the moistening rollers, through the grooves 76, in their respective cross-heads, to the takeup rollers 133, and 134. Said rollers 133, are suitably mounted for rotation on the brackets 135, and the rollers 134, whose respective shafts 136, and 137, are journaled in the brackets 135, and standards 138, are arranged to contemporaneously rotate by engagement of their bevel gears 140, and 141. The shaft 136, is also provided with the miter gear 144, which is driven by the miter gear 145, through the toothed engagement with the miter gears 146, on the vertical shaft 147. The miter gear 145, is secured to the shaft of the gear 148, which is in toothed engagement with the pinion 150, on the shaft 38.

The web 13, having been reinforced and perforated by the punching mechanism is progressed in a horizontal plane to the cutting mechanism, with its edges disposed in the grooves 152, of the guides 153, which are secured to the respective frames 2, and 3, by the brackets 154, as best shown in Fig. I. Said cutting mechanism is conveniently supported by the bearing standards 158, and hangers 159, and comprises opposed cross-heads 160, and 161, having horizontally extending webs 162, and 163, respectively carrying corner cutting dies 165, and their co-operating die plates 166. Said cross-heads also respectively carry the upper severing blades 168, and the lower severing blade 169. The gear 37, of said cutting mechanism is arranged to rotate in the direction of the arrow shown in Fig. II, and to mesh with the gear 175, whose shaft 176, is journaled in the bearings 177, in the standards 158, and pro-

vided with the gear 179. Said gear 37, also meshes with the gear 180, whose shaft 181, is journaled in the bearings 182, in the hangers 159, and provided with the gear 183. The gears 175, and 179, mesh with the idle gears 185, which are mounted on the stud shafts 186, on the standard 158, and mesh with the gears 187, whose shafts 188, are journaled in the bearing 189, in the standards 158. Said shafts 188, are provided with wrist plates 190, having the eccentric pins 191, engaging the connecting rods 192, to which the cross-head 160, is rigidly secured. The gears 180, and 183, mesh with the gears 193, whose shafts 194, are journaled in the bearings 195, in the hangers 159, and provided with the wrist plates 196, having the eccentric pins 198, engaging the connecting rods 200, to which the cross-head 161, is rigidly secured.

The cross-heads 160, and 161, are maintained in alinement by the guide bars 201, which are secured to the connecting rods 200, and are arranged to reciprocate in the slide-ways 202, in the connecting rods 192, being prevented from displacement by the cleats 203.

At each reciprocation of the cross-heads a notch 204, is made in the opposite edges of the web 13, by the corner cutting dies, and the web is cut transversely by the severing blades in alinement with the apexes of said notches as indicated by the dot and dash line in Fig. XII. In order to prevent the web 13, riding up with the dies 165, and thereby buckling; the stripper fingers 205, are arranged in parallel relation, and approximate to the cutting edges of said dies 165. Said fingers are conveniently mounted on the plungers 206, which are arranged to reciprocate in their plunger casings 207, and are normally shifted outward by the springs 208, but limited in their movement by the pins 209, which extend through the slots 210, in said casings, as best shown in Figs. V, and VII. It may be here noted that as the dies 165, and their die plates 166, approximate each other the plunger 206, is pressed up in its casing 207, by engagement of the fingers 205, with the web 13, overlying the die plates 166, and as said dies and plates are separated the plunger and fingers are shifted by the spring 208, sufficiently to press the web 13, from the dies, to insure its free movement with respect thereto. Likewise the severing blades 168, are provided with the stripping bar 212, which is mounted on the slide rod 213, arranged for vertical reciprocation relatively to the severing blade 168, and normally shifted downward by the coiled spring 215 and arranged to impinge on the web 13. When the severing blades are in their cutting position the stripping bar 212, is uplifted by the lower severing blade 169, against the tension of the spring 215, as shown in Fig. III,

but when said severing blades are separated, the stripping bar is shifted below the cutting edge of the upper severing blades 168, and thereby frees the web 13, therefrom.

As best shown in Fig. V, the shaft 39, is provided with the gear 220, in toothed engagement with the gear 221, on the shaft 222, which is journaled in the bearing blocks 223, (see Fig. III); arranged to be vertically adjusted by the set screw 224. Said shafts 39, and 222, respectively comprise co-operating slitting disks 225, and 226, arranged to divide the web centrally on the line 228, in Fig. XII.

Slightly in advance of the slitting disks 80 and disposed between the guides 153, are the co-operating web feeding disks 230, and 231, on the respective shafts 232, and 233. The shaft 232, being journaled in the frame 234, and provided with the gear 235, in toothed engagement with the gear 220, through the idler 236. Said gear 235, is also in toothed engagement with the gear 238, on the shaft 233, which is journaled in the bearing blocks 239, adjusted by the set screws 240.

As the tags 241, are severed from the web 13, they are caught between the discharging rollers 242, and 243, on the respective shafts 244, and 245, the former being journaled in the standards 247, and the latter being journaled in the bearing blocks 248, which are upheld under tension of the spring 249, as shown in Fig. II. Guiding wires 250, are arranged to direct the tags between the rollers 242, and 243, and are adjustably secured by the set screws 251, to the lugs 252, of the cross-beam 253, supported upon the standards 247. If however, it is desired to make tags in gangs, that is, to produce tags in series that are not entirely severed, for instance, in a series of four tags as shown in the two gangs 300, and 301, in Fig. XIV, the counting device, that is the winged shaft 255, must be removed from the machine, and the severing blades 168, whose cutting edges are curved as shown in Fig. V, so adjusted that they normally will not entirely sever the tag from the web 13, but will slit it as shown by the lines 304, in Fig. XIV.

The blades 168, are adjustably secured to the auxiliary cross-head 305, by the screws 306, which extend through slots 307, in said blades in threaded engagement with said auxiliary cross-head. Said auxiliary cross-head 305, is carried by the cross-head 160, and is arranged for vertical reciprocation relatively thereto in the guides 309, and provided with lugs 310, to which are pivoted the links 311, having rollers 312, journaled thereon, and arranged to traverse the grooves 313, in the cams 315, to reciprocate the blades 168, relative to the cross-head 160, at predetermined intervals. Said cams 315, are mounted on the shaft 316, which is journaled in bearings 318, in the upper ends of the connecting rods 130.

192, and which comprises the gear 319, in toothed engagement with the gear 320, on the wrist pin 191.

It may be noted that at every fourth reciprocation of the cross-head 160, carrying the blades to their cutting position, the cross-head 305, is shifted downward relatively to the cross-heads 160, by the action of the cams 315, so that the curved edges of the blades 168, will co-operate with the blade 169, to sever the web its entire width, and the two gangs of four tags each, as shown in Fig. XIV, are deposited side by side upon the conveyer belt 262.

15 Although I have shown the blades 168, having curved cutting edges, it is to be understood that a single blade which may be co-extensive in length with the blade 169, and having a straight cutting edge may be 20 used when single tags are to be severed from the web.

In order that the punching and cutting mechanisms may be adjusted to accurately time their movements relatively; the gear 37, 25 is divided centrally in a plane at right angles to its axis, and comprises the toothed annulus 322, which has slots 323, extending concentrically, through which the tap bolts 324, extend in threaded engagement with the 30 gear 37. As best shown in Fig. I, the gear 175, is in toothed engagement with the gear 37, while the gear 34, is in toothed engagement with its annulus 322. It may be seen 35 that the annulus 322, is capable of being slightly rotated relatively to the gear 37, to adjust the relative timing of the tag forming mechanisms, and secured to said gear 37, in any desired adjusted position by the bolts 324, thus forming a substantially integral 40 gear.

It may be observed that the parts of the machine that directly come into contact with the webs in forming the tags, travel with said webs at the moments of contact, and thereby 45 permit their free progression without the slightest retardation.

I do not desire to limit myself to the precise details of construction and arrangement herein set forth, as it is obvious that various 50 modifications may be made therein, without departing from the essential features of my invention.

I claim:

1. In a tag machine, the combination with 55 reciprocatory cross-heads; of blades carried by said cross-heads arranged to partially sever tags from the tag web; and, means whereby one of said blades may be automatically shifted relatively to its cross head, at 60 predetermined intervals, to sever in a gang, the series of tags thus formed, substantially as set forth.

2. In a tag machine, the combination with 65 reciprocatory cross-heads; of blades carried by said cross-heads arranged to partially

sever tags from the tag web; and cams mounted on and carried by one of said cross heads arranged to automatically shift its respective blade relatively thereto at predetermined intervals to sever in a gang, the series of tags 70 thus formed, substantially as set forth.

3. In a tag machine, the combination with opposed reciprocatory cross-heads; of blades carried by said cross-heads arranged to partially sever tags from the tag web; cams 75 mounted on and carried by one of said cross-heads arranged to automatically shift its respective blade relatively thereto at predetermined intervals to sever in a gang, the series of tags thus formed; and, means arranged to 80 adjust said blades, substantially as set forth.

4. In a tag machine, the combination with opposed reciprocatory cross-heads; of blades mounted on and carried by said cross-heads arranged to partially sever tags from the tag 85 web; rotary cams arranged to automatically shift one of said blades relatively to its cross head at predetermined intervals to sever in a gang, the series of tags thus formed; bearings supporting said cams, mounted on said cross-heads; and, means arranged to adjust said blades with respect to the axis of said cam, substantially as set forth.

5. In a tag machine, the combination with a reciprocatory cross-head; of a cutting blade 95 mounted in said cross-head and arranged to normally reciprocate therewith, to partially sever the tags from the tag web, but capable of reciprocation relatively thereto; cams mounted on and carried by said cross-head; links connecting said cams and blade whereby it may, at predetermined intervals, be shifted to sever in a gang, the series of tags thus formed, substantially as set forth.

6. In a tag machine, the combination with 105 punching mechanism; of cutting mechanism arranged to operate in definite relation to said punching mechanism; a gear connecting said mechanisms, and comprising relatively rotatable sections, divided in a plane at right angles to its axis; and being in toothed engagement with the gears of punching and cutting mechanism respectively; and, means arranged to rigidly unite said sections, substantially as set forth.

7. In a tag machine, the combination with 115 opposed reciprocatory cross-heads; of co-operating cutting dies carried by said cross-heads; and spring-pressed stripping fingers arranged to engage the web while being cut, 120 and to shift the web from said dies and then withdraw from said web after the cutting operation, substantially as set forth.

8. In a tag machine, the combination with 125 opposed reciprocatory cross-heads; of a cutting blade secured to one of said cross-heads; an auxiliary cross-head mounted on and carried by the other of said cross-heads and arranged to reciprocate relatively therewith at predetermined intervals different from the 130

- intervals of reciprocation of said opposed crossheads; and, a cutting blade adjustably secured to said auxiliary cross-head, substantially as set forth.
5. In a tag machine, the combination with opposed reciprocatory cross-heads; of a cutting blade secured to one of said cross-heads; an auxiliary cross-head carried by the other of said cross-heads and arranged to reciprocate relatively therewith at predetermined intervals; cams supported in rigid relation with the latter cross-head, arranged to reciprocate said auxiliary cross-head; and a blade comprising a curved cutting edge adjustably secured to said auxiliary cross-head, substantially as set forth.
10. In a tag machine, the combination with opposed reciprocatory cross-heads; of a cutting blade secured to one of said cross-heads; an auxiliary cross-head carried by the other of said cross-heads and arranged to reciprocate relatively therewith at predetermined intervals; cams supported in rigid relation with the latter cross-head, arranged to reciprocate said auxiliary cross-head; a blade comprising a curved cutting edge adjustably secured to said auxiliary cross-head; and a stripper bar arranged to normally press the web from said blade, substantially as set forth.
15. In a tag machine, the combination with opposed crossheads; of means carried by said crossheads, arranged to impinge on the tag web; a blade secured to one of said crossheads; a blade mounted for relative reciprocation in the other crosshead; means whereby said blades are shifted by said crossheads to partially cut the tag web; and means whereby at predetermined intervals the relatively movable blade is further shifted automatically, with respect to the cross-head which carries it to sever said web, substantially as set forth.
20. In a tag machine, the combination with opposed crossheads; of alined blades carried by said crossheads, arranged to partially cut the tag web; means mounted on and carried by one of said crossheads arranged to further shift its blade relatively thereto, to sever said partially cut web, substantially as set forth.
25. In a tag machine, the combination with opposed crossheads; of alined blades carried by said crossheads, arranged to partially cut the tag web; means mounted on and carried by one of said crossheads arranged to further shift its blade relatively thereto, to sever said partially cut web; and a stripper bar arranged to press said web from the blade and then withdraw from said web, substantially as set forth.
30. In a tag machine, the combination with opposed crossheads; of means carried by said crossheads arranged to impinge on the tag web; a cutting tool carried by one of said crossheads, arranged to coöperate with said impinging means to cut the web; and means mounted on and carried by said cross-head arranged to automatically reciprocate said cutting tool relatively thereto, substantially as set forth.
35. In a tag machine, the combination with opposed crossheads; of hollow plungers carried by said crossheads, arranged to impinge on the tag web; a cutting tool carried by one of said crossheads arranged to reciprocate within said plungers and cut said web at the impinged region; and means carried by said crosshead, arranged to reciprocate said cutting tool relatively thereto, substantially as set forth.
40. In a tag machine, the combination with opposed crossheads; of alined blades carried by said crossheads, arranged to partially cut the tag web; means mounted on and carried by one of said crossheads arranged to further shift its blade relatively thereto, to sever said partially cut web, substantially as set forth.
45. In a tag machine, the combination with opposed crossheads; of alined blades carried by said crossheads, arranged to partially cut the tag web; means mounted on and carried by one of said crossheads arranged to further shift its blade relatively thereto, to sever said partially cut web, substantially as set forth.
50. In a tag machine, the combination with opposed crossheads; of alined blades carried by said crossheads, arranged to partially cut the tag web; means mounted on and carried by one of said crossheads arranged to further shift its blade relatively thereto, to sever said partially cut web, substantially as set forth.
55. In a tag machine, the combination with opposed crossheads; of alined blades carried by said crossheads, arranged to partially cut the tag web; means mounted on and carried by one of said crossheads arranged to further shift its blade relatively thereto, to sever said partially cut web; and a stripper bar arranged to press said web from the blade and then withdraw from said web, substantially as set forth.
60. In a tag machine, the combination with opposed crossheads; of means carried by said crossheads arranged to impinge on the tag web; a cutting tool carried by one of said crossheads, arranged to coöperate with said impinging means to cut the web; and means mounted on and carried by said cross-head arranged to automatically reciprocate said cutting tool relatively thereto, substantially as set forth.
65. In a tag machine, the combination with opposed crossheads; of hollow plungers carried by said crossheads, arranged to impinge on the tag web; a cutting tool carried by one of said crossheads arranged to reciprocate within said plungers and cut said web at the impinged region; and means carried by said crosshead, arranged to reciprocate said cutting tool relatively thereto, substantially as set forth.
70. In a tag machine, the combination with opposed crossheads; of hollow plungers carried by said crossheads, arranged to impinge on the tag web; a cutting tool carried by one of said crossheads arranged to reciprocate within said plungers and cut said web at the impinged region; and means carried by said crosshead, arranged to reciprocate said cutting tool relatively thereto, substantially as set forth.
75. In a tag machine, the combination with opposed crossheads; of hollow plungers carried by said crossheads, arranged to impinge on the tag web; a cutting tool carried by one of said crossheads arranged to reciprocate within said plungers and cut said web at the impinged region; and means carried by said crosshead, arranged to reciprocate said cutting tool relatively thereto, substantially as set forth.
80. In a tag machine, the combination with opposed crossheads; of hollow plungers carried by said crossheads, arranged to impinge on the tag web; a cutting tool carried by one of said crossheads arranged to reciprocate within said plungers and cut said web at the impinged region; and means carried by said crosshead, arranged to reciprocate said cutting tool relatively thereto, substantially as set forth.
- In testimony whereof, I have hereunto signed my name, at Bordentown in the State of New Jersey this thirteenth day of January 1906.
